Primary Examiner — Patricia A Palasik(74) *Attorney, Agent, or Firm* — Fish & Richardson P.C.(57) **CLAIM**The ornamental design for a debris container, substantially
as shown and described.

DESCRIPTION

FIG. 1 is a perspective view of the debris container.

FIG. 2 is a front view thereof.

FIG. 3 is a back view thereof.

FIG. 4 is right side view thereof.

FIG. 5 is left side view thereof.

FIG. 6 is top view thereof; and,

FIG. 7 is bottom view thereof.

The broken lines illustrate environmental features that form
no part of the claimed design.

1 Claim, 7 Drawing Sheets
